UNITED STATES PATENT OFFICE.

HENRY DIECKS, OF EASTPORT, MAINE.

CAN-SEAMING MACHINE.

No. 819,526.

Specification of Letters Patent.

Patented May 1, 1906.

Application filed December 6, 1904. Serial No. 235,692.

To all whom it may concern:

Be it known that I, HENRY DIECKS, a citizen of the United States, residing at Eastport, in the county of Washington and State of Maine, have invented a new and useful 5 Can-Seaming Machine, of which the following is a specification.

This invention relates to mechanism employed for the seaming of cans, and has for its 10 principal object to provide a novel mechanism for quickly and effectively seaming tin cans without the employment of solder and with or without the employment of an adhesive cement.

15 A further object of the invention is to provide a double seaming-machine in which provision is made for preventing the wear that usually takes place as a result of sliding friction on the members which carry the roller-dies, such parts wearing away rapidly in the machines in ordinary use and requiring constant adjustment and frequent renewal of the parts.

20 A still further object of the invention is to provide a novel form of seaming-machine which to some extent is automatic in its nature, the seaming operation and movement of the parts automatically stopping at a predetermined time and the seamed can being 25 removed from engagement with the seaming devices.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, 30 portions, size, and minor details of the structure may be made without departing from the spirit or sacrificing any of the advantages of the invention.

In the accompanying drawings, Figure 1 is 35 a side elevation of a can-seaming machine constructed in accordance with the invention. Fig. 2 is a plan view of the same. Fig. 3 is a detail sectional view through the chuck and illustrating the positions of the die-actuating 40 cams, the view being taken on the line 3-3 of Fig. 2. Fig. 4 is an inverted plan view illustrating the construction of the roller-die carriers and their supporting devices. Fig. 5 is a detail perspective view of the cam for controlling movement of the forming-die. Fig. 55 6 is a sectional elevation of a portion of the

machine on the line 6-6 of Fig. 2. Fig. 7 is a plan view, and Fig. 8 an elevation, of one of the cam-controlled levers. Fig. 9 is a plan view, and Fig. 10 is an elevation, of one of the roller-die-carrying members. Fig. 11 is a side elevation of the lower die. Fig. 12 is a similar view of the seam-flattening die.

Similar numerals of reference are employed to indicate corresponding parts throughout the several figures of the drawings.

The working parts of the machine are supported on a suitable frame including a base 10, a standard 11, and a horizontally-disposed arm 12. The standard is provided 70 with a bracket 13, in which are formed bearings for the reception of a horizontally-disposed shaft 13^a, having fast and loose pulleys 14 and a bevel-gear 15, the latter intermeshing with a bevel-gear 16 on a shaft 17, that 75 extends vertically through the standard and is provided at its upper end with a worm 18 and at a point intermediate of its length with a pinion 19, the latter projecting through suitable openings formed in the front and 80 rear walls of the standard.

Secured rigidly to the outer portion of the arm 12 is a stationary shaft 21, on which is mounted a revoluble disk 22, the latter being supported by an annular flange 23, projecting 85 outward from the lower end of the shaft 21. The periphery of this disk is toothed to form a gear 24, that intermeshes with the pinion 19 and receives movement therefrom.

On the lower end of the shaft 21 is a non-circular socket 25, receiving a correspondingly-shaped shank 26, that projects upward from a chuck 27, the chuck being stationary and held from downward movement by a pin 29, fitting within a slot 30 in the lower end of 90 the shaft, and under normal conditions there is sufficient space between the top of the chuck and the wall of the recessed disk to 95 permit upward movement of said chuck for a purpose hereinafter described.

The chuck is provided with a cam-groove 31 of a contour corresponding to that of the cans to be operated upon, and the inner wall of said groove forms the boundary of a depending integral block 32, that fits within a 100 recess formed in the top of the can, this block constituting a stationary anvil for supporting the can during the seaming operation.

The revoluble disk is provided with a pair of perforated bosses 34, through which extend 105 perforated bosses 35, projecting from the upper faces of levers 36 and constituting the

axis of swinging movement of said levers. The upper ends of the bosses 35 are threaded for the reception of suitable nuts 37, by which the levers are retained in place. From the lower face of each lever depends a block 38, having a vertically-disposed groove 39, that forms practically a continuation of the opening of the boss, but is of angular form in cross-section, while the upper portion of the opening in the boss is preferably circular, although this is not essential. Each of the levers 36 is approximately crescentic in form and carries at its inner end an antifriction-roller 40, that fits into the cam-groove 31, the shape of the latter dictating the course of movement of the antifriction-roller, and, as previously described, the chuck may be moved vertically, so that, if desired, the rollers may be disengaged from the cam-groove 31 for purposes of renewal or repair.

On the shaft 21 at a point above the disk is arranged a revoluble sleeve or collar 42, having an annular groove 43 and provided with a pair of lugs 44, these being connected by vertical rods 45 to a cross-bar 46, that is arranged somewhat above the top of the arm 12. The rods 45 extend through guiding-openings in lugs 47, projecting from the arm 12, and between the upper faces of these lugs 25 and the cross-bar 46 are arranged compression-springs 48, that tend normally to hold the sleeve or collar in an elevated position.

Fitting in the groove 43 of sleeve 42 is a collar 50, from which project two diametrically-opposed arms 51. The outer ends of these arms are provided with bosses having openings for the passage of the upper ends of cam-rod 52, and these rods are threaded for the reception of suitable locking-nuts 53, by 30 which they may be first adjusted and then firmly locked in position. The cam-rod pass downward through the openings in the bosses 35 and at their lower ends are provided with cams 54, that are of angular form in sectional plan and fit within the correspondingly-shaped recesses 39 in the pendent bosses 38.

At a point intermediate the ends of each lever 36 is pivoted a die-carrying lever 56. These levers are approximately crescentic in form, and the inner end of each is provided with a roller-die, one being a seam-forming die 57 and the other a flattening-die 58, as is well understood in this art. The opposite or outer end of each lever 56 is reduced in 55 width and is provided with a threaded opening 59 for the passage of a screw 60, the latter being arranged for engagement by the inclined face of the cam 54, and when so engaged the roller-dies carried by said levers 60 are rendered operative. When not engaged, the roller-dies are free to swing to a limited extent and will not operate on the cans.

In suitable bearings 61 at the top of the frame is arranged a horizontally-disposed shaft 62, having at one end a worm-wheel

63, that is mounted loosely on the shaft and is in constant mesh with the worm 18. On this shaft is a clutch 64, one member of which has a projecting pin or roller 65, which may be engaged by a clutch-operating arm 66, carried by a rock-shaft 67. The rock-shaft is mounted in a bearing formed in a projection 68, projecting from the frame, and at that end opposite the clutch-operating arm is provided with a rocker-arm 69. The opposite 70 end of the arm 69 is connected by a rod 70 to the inner end of a manually-operable lever 71, pivoted on a pin 72, that is carried by a bracket 73, projecting from the frame. At a point intermediate the ends of the rocker-arm 69 is an antifriction-roller 74, which may enter a recess 75, formed in a disk 76, that is keyed or otherwise secured to the horizontal shaft 62, and when said roller enters the recess the arm 66 will descend, and its beveled 85 end portion will engage with the pin or roller 65 and move the latter outward until the clutching member 64 is disengaged from the worm-wheel, so that the latter may rotate freely on the shaft without effecting movement of said shaft.

At the forward end of the shaft 62 is a cam 79, adapted to engage a pin or antifriction-roller 80, projecting from the cross-bar 46, and when this cam turns the bar and the rods 45 will be forced downward, and the movement will be transmitted to the two cam-rod 52, thus setting the roller-dies into operation.

The bracket 73, hereinbefore referred to, forms, in connection with a second bracket 82, bearings for the reception of a vertically-disposed spindle 83, that is provided at its upper end with a table 84 of a contour corresponding to that of the can to be seamed and on which the can is placed and then moved upward for engagement by the seaming-dies. Near the lower portion of the spindle 83 is secured a collar 85, connected to the lever 71 by a two-part link 87, and the two members of the link being separated by a yieldable cushion 88, so that slight independent play of the parts will be permitted. The rear end of the operating-lever 71 is connected to the rod 70, and on said rod 70 is a collar 88, between which and the lug 89, projecting from the frame, is arranged a helical compression-spring 90, that tends normally to depress the rod and keep the roller 74 in contact with the periphery of the recessed disk 76.

In the operation of the device a can to be seamed is placed on the table 84 and the latter is moved upward by depressing the handled end of the operating-lever 71, so that the top of the can will be engaged by the block 32, and these parts will then remain stationary during the whole of the seaming operation. Upward movement of the can results also in an upward movement of the rod 70, and the roller 74 leaves its normal position in 130

the recess 75, so that the constantly-rotating worm 18 transmits movement through the worm-wheel 63 to the shaft 62. At the same time the constantly-rotating pinion 19 is slowly revolving the disk 22. The can being now in correct position and the roller-die bearing loosely against its edges, the turning of the cam 79 forces the two cam-rods 52 down. The cams at the lower ends of the rods 52 are arranged at different levels, the cam which forces the forming-die to operative position being of the character shown in Fig. 5 and operating in advance of the cam employed for forcing the flattening-die into operative position. It will be observed that after the cam-face of the rod 52 (shown in Fig. 5) has passed beyond the set-screw 60 said set-screw may enter a recess 54', formed in the cam-face, and thus permit the forming-die to move from active engagement with the seam during the time the opposite cam is moving the flattening-die to operative position. In order to provide for more accurate movement and prevent excessive play, the two levers 56 are connected to the bosses 38 by means of light tension-springs 81. On downward movement of the cam-rods 52 the cam of the forming-die will first move to operative position, and the forming-die will thereupon move into engagement with the edge of the can and will be gradually forced thereagainst, this operation resulting in the formation of a seam. As the operation progresses the cam 79 will still further depress the bar 46, and the cam-rods 52 and the second cam 54 will be forced to operative position, causing the lever 56, that carries the flat pressing-die 58, to come into operative engagement with the formed seam, flattening the same. When the can has been raised and the roller 74 has been moved from its recess 75, the operator will release the handle, and the roller 74 then rides on the periphery of the disk 76 until the shaft 62 has made one complete revolution, this resulting in the seaming of the can. The spring 90 then comes into play as the recess 75 again approaches a position under the roller 74, and the latter is held down into the recess. This member results in moving the clutch-operating arm 66 to a position to engage the pin 65, and the members of the clutch are separated. Operative movement of the shaft 62 then ceases, and at the same time downward movement of the rod 70 causes the corresponding movement of the lever 71 and table 84, so that the seamed can may be readily removed from position.

On reference to Fig. 4 it will be seen that the under surface of the gear-wheel 24 is provided with two slots 82', arranged on curved lines struck from the centers of swinging movement of the levers 36. This permits the raising of the centrally-disposed cam-disk 27 until the rollers 40 are wholly free from the cam-groove, nuts 53 being first loosened, af-

ter which the levers 36 may be swung outward, the antifriction-rollers 40 traveling through the slots 82 until they are clear of the periphery of the gear. This permits of any necessary adjustment or renewal of the parts.

Having thus described the invention, what is claimed is—

1. In a can-seaming machine, a lever having a pivotal support at one end, a pin disposed at the opposite end, a grooved cam receiving said pin, a second lever pivoted at a point intermediate its ends to the first lever, a roller-die carried by one end of the second lever, and an adjustable cam arranged near the pivotal point of the first lever and adapted to engage with the second lever and force the roller-die carried thereby into engagement with the can. 75

2. In a can-seaming machine, a lever having at one end a perforated boss and provided with a second grooved boss in alignment with the first, an antifriction-roller arranged at the opposite end of the lever, a grooved cam receiving the antifriction-roller, a second lever pivoted at a point intermediate its ends to the first lever, a roller-die at one end of the second lever, an adjustable screw at the opposite end of the second lever, a slidable cam guided by the two bosses and having an inclined face for engagement with said screw, and means for operating the cam. 90

3. In a can-seaming machine, the combination with a revoluble disk, of means for revolving the same, a pair of sets of levers carried by said disk, each set of levers comprising a carrying-lever pivoted at one end to the disk and provided at the opposite end with an antifriction-roller, a die-carrying lever pivoted to the main lever, one of said dies being arranged to form a seam, and the other to flatten the same, and a pair of cams movable through the main levers and adapted to engage the die-carrying levers, movement of the cams in one direction serving to force the forming-die into engagement with a can in advance of the operation of the flattening-die, and to effect the removal of the forming-die from the work during the operation of the flattening-die. 105 110

4. The combination in a can-seaming machine, of a toothed disk, a revoluble pinion engaging the disk, a rigid shaft supporting said disk, a vertically-movable chuck supported by the shaft and provided with a cam-groove, and an anvil, a pair of sets of levers pivoted to the disk, antifriction-rollers carried by one set of levers and entering the cam-groove, seaming-dies carried by the second set of levers, vertically-movable cam-bars for engaging and locking the seaming-die-carrying levers, a collar revoluble with the disk and having arms for supporting said cam-rods, a stationary sleeve having a groove for the reception of said collar and mounted on the shaft, 125 130

lugs projecting from the sleeve, a pair of rods connected to said lugs, a cross-bar connecting the upper ends of the rods, an antifriction-roller on said cross-bar, a revoluble cam-shaft, a cam mounted thereon and engaging the antifriction-roller, a worm-wheel on the cam-shaft, a worm-shaft, a worm mounted thereon and meshing with the worm-wheel, a clutch for engaging the worm-wheel with its shaft, a can-receiving platform, an elevating-lever for the platform, a rock-shaft, a rocker-arm, a clutch-operating lever secured to the rocker-arm, a rod extending between the rocker-arm and the operating-lever, a recessed disk on the cam-shaft, and a roller carried by said rocker-arm and adapted to engage the recessed disk.

5. The combination in a can-seaming machine, of a revoluble carrying device, a pair of cam-actuated levers supported thereby, roller-dies, one for the formation of a seam and the other for the flattening of the same,

roller-die-carrying levers pivoted to the cam-actuated levers, and cams for successively engaging the carrying-lever of the forming-die and the carrying-lever of the flattening-die.

6. The combination in a can-seaming machine, of a revoluble gear having a pair of arcuate slots, levers pivoted thereto, dies carried by said levers, antifriction-rollers projecting from the levers and movable outward through said arcuate slots, and a vertically-adjustable disk arranged within a recess in the gear-wheel and provided with a cam-groove for the reception of said antifriction-rollers.

In testimony that I claim the foregoing as my own I have hereto affixed my signature in the presence of two witnesses.

HENRY DIECKS.
